UNITED STATES PATENT OFFICE.

FREDERIC L. GERKE, OF NEW YORK, N. Y.

NON-GLARE HEADLIGHT.

1,354,739,

Specification of Letters Patent. Patented Oct. 5, 1920.

Application filed September 11, 1919. Serial No. 323,051.

To all whom it may concern:

Be it known that I, FREDERIC L. GERKE, a citizen of the United States, residing at New York, in the county of New York and State of New York, have invented certain new and useful Improvements in Non-Glare Headlights, of which the following is a specification.

This invention relates to non-glare head-lights, and the primary object thereof is to provide a headlight in which the customary lens or glass cover is replaced by a complete or unitary structure which embodies a lens having an integral hood to deflect the upper light rays downwardly and at the same time to cut-off the rays from the vision of approaching drivers, and which further deadens the lower light rays from the lamp so as to eliminate all glare.

20 In the drawings:

Figure 1, is a longitudinal vertical sectional view of the invention; and

Fig. 2, is a front elevation.

In proceeding in accordance with the present invention, a lens 1 is employed which is formed with an integral glass hood or vizor 2.

The hood preferably has a straight horizontal bottom and a downwardly and outwardly inclined top, the angle formed between the top and bottom being about 30°, the under face of the hood being coated with preferably milk-white color as indicated at 6. The outer end of the hood terminates at 35 the horizontal center of the reflector 3, so as to cut-off or intercept all upper light rays from the line of vision of pedestrians or approaching car drivers.

The upper half of the lens is of clear glass, while the lower half is coated or otherwise provided with a preferably milk-white color as indicated at 4 so as to deaden the lower light rays from the lamp. The line

of coloring 4 of the lower half of the lens terminates on a horizontal line 5, which is 45 located at the horizontal center of the lens and reflector. With this structure it will be apparent that in going up a hill or the like, the coloring 4 will act to cut-off or intercept the rays from the line of vision of 50 pedestrians or car drivers going down the hill.

The invention is made throughout of a single integral piece of glass constituting a unitary structure, which effectively eliminates all glare. The upper light rays strike the under face of the hood and encountering the white coating 6 will be deflected downwardly onto the road, and since the outer end of the hood terminates at the horizontal 60 center of the lens and reflector, same will cut-off the rays from the line of vision of pedestrians and approaching car drivers. The lower rays of light are deadened or softened by the colored lower half of the 65 lens, the line of coloring coinciding with the termination of the outer free end of the reflector.

What is claimed is:

In a non-glare headlight device for bodily substitution for the ordinary lens of the headlight, a unitary member composed of a lens having an integral light-diffusing hood extending outwardly therefrom and at an angle of substantially 30° thereto, the 75 bottom edges of the hood terminating in substantially straight lines at approximately the horizontal center of the lens, and light-softening material on the lower half of the lens having a straight top edge aligned with 80 the said bottom edges of the hood, the entire upper half of the lens being left plain and completely covered by the hood.

In testimony whereof I affix my signature.

FREDERIC L. GERKE.
